CLAIM

The ornamental design for an incense burner, as shown and described.

DESCRIPTION

The patent or application file contains at least one drawing executed in color. Copies of this patent or patent application publication with color drawing(s) will be provided by the Office upon request and payment of the necessary fee.

FIG. 1 is a right side view of a first embodiment of an incense burner showing my new design;

FIG. 2 is a bottom view thereof;

FIG. 3 is a front view thereof;

FIG. 4 is a rear view thereof;

FIG. 5 is a top view thereof;

FIG. 6 is a perspective view thereof;

FIG. 7 is a right side view of a second embodiment of an incense burner showing my new design;

FIG. 8 is a bottom view of the incense burner shown in FIG. 7;

FIG. 9 is a front view of the incense burner shown in FIG. 7;

FIG. 10 is a rear view of the incense burner shown in FIG. 7;

FIG. 11 is a top view of the incense burner shown in FIG. 7;

FIG. 12 is a perspective view of the incense burner shown in FIG. 7; and,

FIG. 13 is a perspective view of a third embodiment of an incense burner showing my new design.
